UNITED STATES PATENT OFFICE.

SAMUEL G. GILLESPIE, OF CHARLESTON, WEST VIRGINIA.

FENCE-POST.

1,165,589.

Specification of Letters Patent. Patented Dec. 28, 1915.

Application filed September 18, 1913. Serial No. 789,675.

To all whom it may concern:

Be it known that I, SAMUEL G. GILLESPIE, a citizen of the United States, residing at Charleston, in the county of Kanawha, State 5 of West Virginia, have invented certain new and useful Improvements in Fence-Posts; and I do hereby declare the following to be a full, clear, and exact description of the invention, such as will enable others skilled 10 in the art to which it appertains to make and use the same.

This invention relates to improvements in fence posts, and particularly to artificial stone posts.

15 The principal object of the invention is to provide a metal reinforce for the post which includes as one of its features a wire supporting means.

Another object is to provide a support 20 for a fence wire and means for tightening the fence wire to the support whereby slipping of the wire through the support and the sagging of the wire between the posts are prevented.

25 Other objects and advantages will be apparent from the following description when taken in connection with the accompanying drawings.

In the drawings: Figure 1 is a front elevation of a post made in accordance with my 30 invention. Fig. 2 is a vertical longitudinal sectional view on the line 2—2 of Fig. 1. Fig. 3 is a horizontal sectional view on the line 3—3 of Fig. 2.

35 Referring particularly to the accompanying drawings, 10 represents the upwardly tapering body of a concrete or artificial stone post. Embedded in the post and extending longitudinally in parallel relation 40 on opposite sides of the post are the metal reinforcing bars 11. Extending centrally

the length of the post, and embedded therein is a metal reinforcing element represented as a whole by the reference character 12. This reinforcing element comprises a plurality of parallel arranged horizontal portions 13 and a plurality of obliquely arranged and parallel portions 14, these portions 13 and 14 being connected by the loops 15 which project from the center of the face 50 of the post, and constitute the wire supporting means. The fence wires 16 are passed through the loops, and may be simply supported thereby or may be additionally held to the loops by means of the wire stays 55 or ties 17. It will be particularly noted that the reinforcing elements 11 brace the post longitudinally, while the portions 13 and 14 of the element 12 brace the post transversely. Thus the element 12 serves to reinforce the 60 post longitudinally and transversely, and acts as a means to which the fence wires are connected.

What is claimed is:—

In a fence post, a molded plastic body, a 65 metal bar partly embedded therein, said bar bent to form a series of similarly disposed wire retaining members, each member comprising a horizontal portion extending from a point adjacent the rear face through the 70 front face of the post and rebent parallel to itself to reenter the post forming a wire retaining loop and bent obliquely to connect to the rear end of the horizontal portion of the next succeeding member. 75

In testimony whereof, I affix my signature, in the presence of two witnesses.

S. G. GILLESPIE.
